UNITED STATES PATENT OFFICE

JOHN GAIL FAIRLEY, OF HATTIESBURG, MISSISSIPPI

ROAD MACHINE

Application filed October 29, 1929. Serial No. 403,267.

This invention relates to road machines, and more particularly to a road machine designed for reconditioning road surfaces.

The primary object of the invention is to provide a machine of this character which may be moved along over a road surface, the machine being provided with means for loosening the road surface, and means for conveying the loose material to the center 10 of the road to recrown the road.

Another object of the invention is to provide means for adjusting the machine vertically with respect to the road surface, thereby regulating the depth of operation of the 15 blades or spikes that act to loosen the road surface.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made 25 within the scope of what is claimed, without departing from the spirit of the invention.

Referring to the drawings:

Figure 1 is a plan view of a road machine constructed in accordance with the invention.

Figure 2 is a side elevational view thereof.

Referring to the drawings in detail, the road machine embodies a frame including side bars 5 and front and rear bars 6 and 35 7 respectively, the side bars being connected to the front and rear bars at the ends thereof.

Mounted on the side bars 5 at points adjacent to the forward end thereof, are bearing 40 members 8 that accommodate the shaft 9 on which the spikes 10 are mounted, the shaft being shown as provided with reduced end portions that fit in the bearings.

Mounted on one end of the shaft 9, is a 45 sprocket 11 over which the chain 12 operates, the chain 12 also operating over a sprocket rotated by the tractor or machine used in dragging the machine over the road surface.

As clearly shown by Figure 1 of the drawings, one end of the shaft 9 extends an ap-

preciable distance beyond the side bar 5 at one side of the frame, where it is mounted in the bearing 13 secured to the auxiliary frame 14 that extends beyond one side of the frame of the machine.

Operating adjacent to the shaft 9, is a shaft 15 that has its ends positioned in the bearings 16, the shaft 15 supporting the pinion 17 that meshes with the pinion 18 mounted on the reduced end of the shaft 9, 55 so that movement of the shaft 9 is transmitted to the shaft 15. A beveled pinion 19 is also mounted on the shaft 15 and is in mesh with the beveled pinion 20 mounted on one end of the shaft 21 that is mounted in bearings 22 and 23 respectively. Thus it will be seen that rotary movement of the shaft 15 is imparted to the shaft 21 to rotate the shaft.

Blades 24 are secured to the shaft 21 and 70 are arranged helically around the shaft 21, so that as the shaft 21 is rotated, material will be fed inwardly from the outer edge of the road surface over which the machine is moving, to a point adjacent to the crown of the road. Owing to the fact that the shaft 21 is arranged at an oblique angle with respect to the side bars 5, it will be seen that the blades 24 secured to the shaft will have a further tendency to push the material 80 inwardly.

At the rear of the machine, is a bar 25 that has its ends mounted in bearings 26, the bar 25 providing a support for the arms 27 formed with openings to receive the shaft 85 of the roller 28 that rolls over the loosened road surface to pack the road surface.

Extending upwardly from the arm 27 at one end of the roller, is an arm 29 to which the link 30 is connected, the opposite end of the link having connection with the lever 31 that is operated by the attendant to raise and lower the roller 28 to adjust the frame of the machine vertically regulating the depth of operation of the spikes 10 and 95 blades 24.

It might be further stated that the spikes 10 are arranged helically of the shaft 9 so that the digging operation of the spikes will be continuous. Links 32 are provided at 100

the front end of the machine and provide means for connecting the machine to a tractor or similar device whereby the device may be pulled along over the ground surface. A chain 33 has connection with the machine and is adapted to be hooked over the hook 34 to regulate the depth of operation of the spikes and blades.

I claim:

- 19 In a road machine, a frame, a shaft disposed transversely of the frame, spikes arranged helically on the shaft, a shaft disposed diagonally across the frame, one end of the diagonal shaft being disposed near one end of the first mentioned shaft, gearing for transmitting movement of the first mentioned shaft to the later shaft, blades arranged helically around the last mentioned shaft, and means for transmitting movement to the first mentioned shaft.
- 15
- 23

In testimony that I claim the foregoing as my own, I have hereto affixed my signature.

JOHN GAIL FAIRLEY.
